(57) **CLAIM**

The ornamental design for a push-to-talk communicator housing, as shown and described.

DESCRIPTION

FIG. 1 is a perspective view of the present invention;

FIG. 2 is a right side elevational view;

FIG. 3 is a left side elevational view;

FIG. 4 is a front view;

FIG. 5 is a back view;

FIG. 6 is a top view; and,

FIG. 7 is a bottom view.

The broken lines are included for the purpose of illustration and form no part of the claimed design.
